UNITED STATES PATENT OFFICE.

HANS K. LORENTZEN, OF NEW YORK, N. Y.

PORTABLE ELECTRIC LAMP.

1,329,051.

Specification of Letters Patent.

Patented Jan. 27, 1920.

Application filed March 17, 1916. Serial No. 84,817.

To all whom it may concern:

Be it known that I, HANS K. LORENTZEN, a subject of the King of Denmark, residing at New York, in the county of New York and State of New York, have invented certain new and useful Improvements in Portable Electric Lamps, of which the following is a specification.

My invention relates particularly to lamps 10 of the so-called "portable" type.

One of the objects of my invention is to provide simple and effective means for storing the lamp cord and paying it out in such lengths as needed.

15 Another object is to enable the adjustment and setting of the lamp in different angular relations.

A further object is to provide for the supporting of the lamp on walls and the like 20 surfaces, as well as on tables and such usual horizontal supports.

The first of these objects I have accomplished by mounting within a hollow lamp-supporting base, a spring-wound cord reel 25 carrying a ratchet which is held in position with the desired length of cord in use, by a manually controlled spring-pressed pawl.

The different angular adjustments are 30 made possible by mounting the lamp socket in angularly adjustable relation on a supporting post, which, in turn, is rotatably adjustable in a socket on the base, sliding contacts being provided between this post and the reel, and the post being preferably seated 35 in its rotatably adjusted relation by yielding holding means.

A suction cup normally seated in the base and adapted to be extended therefrom when desired for use, provides the means for supporting the lamp on walls and the like 40 places.

Other features of the invention will appear as the specification proceeds.

In the accompanying drawings I have 45 illustrated the invention embodied in a practical and preferred form but it will be understood that changes and modifications may be made without departure from the true spirit and scope of the invention.

50 Figure 1 in said drawings, is a view illustrating the base portion and the shade holder of the lamp in section; Fig. 2 is a horizontal sectional view of the same taken substantially on the plane of the line 2—2 of Fig. 1; Fig. 3 is a side view of the shade

holder, the shade having been detached therefrom; Fig. 4 is a detail sectional view of the manually releasable holding pawl for the cord reel; Fig. 5 is a sectional view of the base portion of the lamp, showing the 60 suction cup projected and in use; Fig. 6 is a bottom plan view of the base; Fig. 7 is a horizontal sectional view taken substantially on the plane of the line 7—7 of Fig. 1.

Referring now to the drawings more in 65 detail, 10 designates the supporting base of the lamp, usually flat on the bottom, as indicated, adapting it for use on a table or the like, and of a size and weight to give the lamp the necessary stability, though not so 70 large or heavy as to be inconvenient for ready handling.

Mounted on the upper side of the base and preferably seated within a depression 11, therein is the cord reel, made up in the 75 illustration of a hollow drum 12, pivoted on a screw stud 13 and carrying at its upper end spaced apart flanges 14—15 receiving between them the lamp cord 16.

The reel is impelled in a direction to wind 80 up the cord by a spring 17, seated in the depression 11, around the drum and connected at one end at 18 to the base and at the other end at 19 to the drum. The reel flanges may extend out over the edges of the depression, 85 as indicated in Fig. 1 so as to cover and protect the winding spring.

A convenient and practical method of 90 constructing the reel is to cup the central portions of the two flanges, as indicated in Fig. 1, so that the cupped portion of one flange will fit inside the cup on the other flange, the two cupped portions thus nesting one within the other and constituting the drum portion of the reel. The flanges 95 may further be reinforced and strengthened by turning annular rims 20 on the edges thereof.

The reel may be locked in position after the necessary length of cord has been unwound therefrom, by means, such as a spring-pressed pawl 21, secured at 22 on the underside of the top or cover 23 of the base and engaging a series of ratchet teeth 24 on the reel. In the illustration these ratchet 105 teeth are cut in the rim 20 of the upper reel flange.

The ratchet teeth are faced so as to permit the unwinding movement of the reel by simply pulling on the cord, the spring- 110

pressed pawl acting as soon as the pull on the cord is released, to hold the reel in that position.

The holding pawl is released to permit the spring to rewind up the cord by means, consisting in the illustration, of a button 25, working through the cover of the base and serving by engagement with the pawl (Fig. 4) at one side of a loop or fulcruming point 26, to lift the nose of the pawl off the ratchet teeth.

Mounted in a socket 27 provided in the top of the base, is the tubular lamp-carrying post 28, provided with contacts 29 and 30 at its lower end engaging contacts 31 and 32 on the reel, the first set of contacts having wires 33 and 34 connected thereto, leading to the lamp socket 35 and the latter set of contacts having the cord wires 36 and 37, connected therewith. The contacts 31 and 32 may be mounted on a plate 38 of insulating material secured to the upper face of the relatively horizontal reel and similarly the contacts 29 and 30 may be mounted on a block 39 of insulation secured in the lower end of the upright post.

The sliding contacts thus provide a means of continuous electrical connection between the reel and post and allow for the rotation of the post in its socket as well as the rotation of the reel within the base.

A firm engagement of the two sets of sliding contacts is provided for in the illustration by a spring 40 engaged at its central portion with a collar 41 on the lower end of the post and bearing at its ends against the underside of the cover 23, this spring serving to draw the post firmly down in its socket and to hold the contacts yieldingly engaged with each other.

The socket is preferably made angularly adjustable on the post, as by mounting it on a ring 42, held clamped by a screw bolt fastening 43 between clamping jaw portions 44 at the upper end of the post. This construction permits of the lamp socket being tilted over at an angle and this, with the rotatability of the post provides for the setting of the lamp in practically any angular relation, the clamp at 43 and the spring-holding device 40, serving to maintain the parts in such relations.

The lamp is made capable of being supported on walls and the like by providing it with a suction cup supporting device 45 normally housed in a recess 46 in the bottom of the base and adapted to be projected into active extended position by a lever 47 to which it may be received at 48. This lever is shown pivoted at 49 at one edge of the base and working in a slot 50 extending across the base to the suction cup recess 46 at the opposite edge thereof. The suction cup is normally held in the withdrawn inactive position by a spring 51 acting on the

lever, and the outward movement of the lever may be limited by a suitable stop, such as that indicated at 52.

The suction cup is used by simply operating on the extended handle portion 53 of the lever so as to project and force the cup into engagement with the wall or other surface. This securing device is also of use when it is desired to secure the lamp in a certain position on a table or other support.

The lamp is usually equipped with a suitable shade 54, and to hold this shade in place in all the tilted and various angular positions of the lamp, I have provided a special holder consisting of a yoke-shaped member 55, doubled upon itself to embrace the tip portion of the lamp 56 and having arms 57 cut out from the top and sides thereof and bent radially outward to form outstanding supports engaged with the shade at 58. The cutting of the shade supporting arms from the sides of the yoke, leaves these sides with spaced-apart portions 59 which can be readily shaped to fit the lamp and which act as spring-holding arms.

The invention, it will be seen, is of simple and inexpensive construction and by reason of its adaptability to different conditions, has a wide range of usefulness.

I claim:

1. A portable lamp comprising a hollow base, a spring-wound cord reel journaled horizontally within said hollow base, an upright lamp-supporting post set in the top of the base in line with the axis of the reel, contacts on the lower end portion of said post and co-operating engaging contacts on the reel.

2. In combination, a lamp base having a depression in the top thereof, a horizontally disposed drum journaled in said depression and provided with spaced outstanding flanges at the upper end thereof forming a cord reel, a drum-winding spring seated in the depression below the outstanding flanges, contacts on the upper side of the reel, a lamp-supporting post mounted on the base above the reel and contacts on the lower end portion of said post engaging the contacts on the reel.

3. In combination, a lamp base, a cord reel mounted thereon, contacts carried by said reel, a lamp-supporting post rotatably mounted on the base terminating above said reel and contacts on said rotatable lamp post engaging the contacts on the cord reel.

4. In combination, a lamp base, a cord reel mounted thereon, contacts carried by said reel, a lamp-supporting post rotatably mounted on the base, contacts on said rotatable lamp post engaging the contacts on the cord reel, and spring means yieldingly holding the lamp post in the position to which it has been rotated.

5. In combination, a lamp base, a cord reel

mounted thereon, contacts carried by said reel, a lamp-supporting post rotatably mounted on the base longitudinally movable toward the cord reel, contacts on said post for engagement with the contacts on the reel and spring means urging the lamp post toward the cord reel.

6. In combination, a lamp base provided with a socket in the top thereof, a lamp-carrying post rotatably seated in said socket, a cord reel journaled on the base, coöperating contacts on the rotatable post and cord reel, and spring means holding the post yieldingly seated in its socket, thereby yieldingly retaining the post in its rotated adjustment with the coöperating contacts of the post and reel engaged.

7. In combination, a base, a cord reel mounted thereon, contacts on the upper face of said reel, an upright post rotatably

mounted on the base above said reel, contacts on the lower end of said post engaging the contacts on the upper face of said reel, means for yieldingly holding the post in its rotatably adjusted position on the base, a lamp socket angularly adjustable on the post and means for yieldingly holding said lamp socket in its angularly adjusted position on the post.

8. In combination, a lamp base provided with a socket in the top thereof, a lamp-carrying post rotatably seated in said socket, a cord reel journaled on the base, coöperating contacts on the rotatable post and cord reel, and a spring engaging the under side of the top of the base and the lamp-carrying post to thereby hold said post yieldingly seated in its socket.

In testimony whereof I affix my signature.
HANS K. LORENTZEN.
